CLAIM

The ornamental design for a camera case, substantially as shown and described.

DESCRIPTION

FIG. 1 is a perspective view of a camera case showing my new design with intermediate portions of the carrying strap broken away and omitted for convenience of illustration;

FIG. 2 is a left side elevational view with a portion of the strap omitted for convenience of illustration;

FIG. 3 is a rear elevational view thereof;

FIG. 4 is a bottom plan view thereof;

FIG. 5 is a right side elevational view thereof, with the closure flaps in open positions; and

FIG. 6 is a bottom rear perspective view thereof.
